UNITED STATES PATENT OFFICE.

F. ROBERT SEIDENSTICKER, OF MERIDEN, CONNECTICUT, ASSIGNOR TO THE
BRADLEY & HUBBARD MANUFACTURING COMPANY, OF SAME PLACE.

DESIGN FOR AN ANDIRON.

SPECIFICATION forming part of Design No. 16,873, dated August 24, 1886.

Application filed July 19, 1886. Serial No. 203,490. Term of patent 7 years.

To all whom it may concern:

Be it known that I, F. ROBERT SEIDENSTICKER, of Meriden, in the county of New Haven and State of Connecticut, have invented a new Design for Andirons; and I do hereby declare the following, when taken in connection with accompanying drawing, to be a full, clear, and exact description of the same, and which said drawing constitutes part of this specification, and represents a perspective view.

This invention relates to a design for andirons; and it consists in the configuration and ornamentation shown in the accompanying illustration and hereinafter described. The legs of the iron form substantially a semicircle, and from which the upright rises, the uprights terminating in the representation of a

face with rays radiating therefrom. The upright itself is of serpentine shape, and the irregular or serpentine shape is continued through the legs. The essential feature of the design, however, is the serpentine-shaped upright terminating in the face, with the representation of rays radiating therefrom. 25

I claim—

The herein-described design for andirons, consisting in the upright rising from the legs in the representation of serpentine form, and terminating in a face, with the representation 30 of rays radiating therefrom, as shown in the accompanying illustration.

F. ROBERT SEIDENSTICKER.
